United States Patent

Des. 235,321
Patented June 10, 1975

235,321

INSTRUMENT FOR DETECTING ELECTROMAGNETIC RESONANT DEVICES

John A. Mahan, James William M. Bee, and John F. Tyson, Ottawa, Ontario, Canada, assignors to Northern Electric Company Limited, Montreal, Quebec, Canada

Filed July 31, 1973, Ser. No. 384,248

Term of patent 14 years

Int. Cl. D10—05

U.S. Cl. D10—78

Fig. 3

Fig. 2

Fig. 1

FIG. 1 is a perspective view of an instrument for detecting electromagnetic resonant devices;

FIG. 2 is a face elevational view of the form shown in FIG. 1, opposite faces being substantially similar in form; and

FIG. 3 is a side elevational view of the form shown in FIG. 1, opposite sides being substantially similar in form.

We claim:

The ornamental design of an instrument for detecting electromagnetic resonant devices, substantially as shown.
